CLAIM

The ornamental design for the remote control device for a diabetes management system, as shown and described.

DESCRIPTION

The present application relates to U.S. patent application Ser. No. 12/039,722, to Daniel Saffer et al., filed Feb. 28, 2008, entitled “Diabetes Management System”, which also relates to U.S. design application Ser. No. 29/304,345, to Daniel Saffer et al., filed Feb. 28, 2008, entitled “Soft Shell for a Diabetes Management System”.

FIG. 1 is a perspective view of a remote control device for a diabetes management system showing our new design;

FIG. 2 is another perspective view thereof shown slightly reduced;

FIG. 3 is a slightly enlarged top view with the bottom being a mirror view of the top of the remote control device for a diabetes management system shown in FIG. 1;

FIG. 4 is a slightly enlarged front view of the remote control device for a diabetes management system shown in FIG. 1;

FIG. 5 is a slightly enlarged back of the remote control device for a diabetes management system shown in FIG. 1;

FIG. 6 is a slightly enlarged right side view of the remote control device for a diabetes management system shown in FIG. 1;

FIG. 7 is a slightly enlarged left side view of the remote control device for a diabetes management system shown in FIG. 1;

FIG. 8 is a slightly enlarged perspective view of the remote control device shown in FIG. 1, wherein the cap covering the plug is removed; and,

FIG. 9 is a front view of the remote control device of FIG. 8. The broken lines showing elements of the display on a remote control device for a diabetes management system in the above described figures illustrate environment and form no part of the claimed design.
